UNITED STATES PATENT OFFICE.

CHARLES H. SNIDER AND LAWRENCE D. MAGRATH, OF CONWAY, SOUTH CAROLINA.

SHAMPOO-COMB.

1,322,639.

Specification of Letters Patent. Patented Nov. 25, 1919.

Application filed November 26, 1918. Serial No. 264,278.

To all whom it may concern:

Be it known that we, CHARLES H. SNIDER and LAWRENCE D. MAGRATH, citizens of the United States, residing at Conway, in the 5 county of Horry and State of South Carolina, have invented new and useful Improvements in Shampoo-Combs, of which the following is a specification.

This invention relates to shampoo combs 10 or devices for treating the hair in the application of either wet or dry shampoos.

The invention has for its object to produce a device of simple and improved construction, the same including a cap having a passageway, and a comb element detachably connected with said cap, said comb element being adapted, according to its construction, for either wet or dry treatment of the hair.

A further object of the invention is to 20 simplify and improve the construction of the comb element.

Further objects of the invention are to simplify and improve the construction, arrangement, and combination and operation 25 of the parts constituting the invention.

With these and other ends in view, which will readily appear as the nature of the invention is better understood, the same consists in the improved construction, novel arrangement and combination of parts which will be hereinafter fully described and particularly pointed out in the claims.

In the accompanying drawing has been illustrated a simple and preferred form of 35 the invention, it being, however, understood that no limitation is necessarily made to the precise structural details therein exhibited, but that changes, alterations and modifications within the scope of the claims may be 40 resorted to when desired.

In the drawing,—

Figure 1 is a side elevation showing the device adapted for the application of wet shampoos.

45 Fig. 2 is a vertical sectional view taken on the line 2—2 in Fig. 1.

Fig. 3 is a transverse sectional view taken on the line 3—3 in Fig. 1.

Fig. 4 is a bottom plan view of the cap or bonnet.

Fig. 5 is a top plan view of the comb for liquid applications.

Fig. 6 is a side view of the comb for dry applications.

Fig. 7 is a plan view of the same.

55

Fig. 8 is a vertical sectional view showing the comb for dry applications assembled with the cap or bonnet.

Reference will first be had to Figs. 1—4, wherein corresponding parts are denoted by 60 like characters.

The cap or bonnet A of the improved device consists of a disk 15 having a circumferential downwardly extending flange 16 and a central opening 17, the latter being 65 for the reception of an inlet nozzle and handle 18 having a flaring or funnel-shaped discharge opening 19 that flares in the direction of the circumferential flange 16. The nozzle 18 has a flexible tube 20 connected 70 therewith and whereby it may be connected with a suction pump or with a source of supply of liquid according to the use to which the device is to be put.

The liquid comb B consists of a cylindrical 75 shell or body 21 having a downwardly extending circumferential series of teeth 22, the upper ends of which are inset with respect to the external perimeter of the shell, the upper ends of the teeth being connected 80 with an internal cylindrical sleeve 23, the latter being located within the shell 21 and substantially concentric therewith, the space 24 intermediate the shell 21 and the sleeve 23 communicating with bores 25 extending 85 through the teeth 22, the latter being cut off obliquely at their lower ends as indicated at 26. The upper end of the sleeve 23 has a conical cap or closure 27, which, if desired, may be integral therewith, the apex of said 90 closure lying within the flaring nozzle 18 so that said closure will act as a spreader to direct any fluid or liquid entering in the nozzle in the direction of the internal circumference of the cylindrical shell 21.

95 The cap or bonnet A has been shown as being threadedly connected with the nozzle 18 as well as with the comb B; it is to be understood however, that the parts may be connected together frictionally or in any other 100 convenient and well known manner, and also that washers or gaskets or like instrumentalities of a well known character may be employed in order to make the joints between the parts perfectly tight.

105 The comb which is used for dry applications is designated by C. Said comb is of substantially cylindrical shape and it is

formed or provided with a downwardly extending circumferential series of teeth 28. The cylindrical body C is of annular shape to provide for engagement with the nozzle 18 which engages the axial opening 29. The comb B is also adapted to be fitted in the cap or bonnet A with which it may be frictionally threaded or otherwise engaged.

When the device is to be used for liquid applications, the comb B is connected with the cap or bonnet A, and the tube 20 is connected with a source of supply of water or other liquid which may be forced in any desired manner through the tube 20 and the nozzle 18 in the direction of the conical closure 27 of the sleeve 23 whereby the liquid is deflected in the direction of the inner wall of the shell 21, filling the space 24 and being eventually forced out through the bores 25 of the teeth 22. The comb is applied with a rotary or gyratory motion to the head of the person who is being shampooed, soap or like material having previously been applied to the hair if desired. In this manner the dandruff and other impurities will become loosened and will be discharged with the water. When a wet application is not desired, a jet of air may be substituted for the liquid, the same being forced through the device in precisely the same manner as the liquid, loosening the dandruff and impurities and carrying the same off to the atmosphere. When the device is to be used in connection with the comb C, suction will be substituted for an air jet, and the dandruff and other impurities loosened by the rotary or gyratory movement of the comb C will now be carried off to the pump or suction device used for setting up suction.

As will be seen from the foregoing description, a device of simple construction has been provided which will be particularly

useful for maintaining the hair and scalp in a clean and healthy condition. The parts of the device may be made of any suitable or appropriate material, it being however, understood that in the construction of the device some metal, such as aluminum, is preferably employed which is non-corrodible and which may be subjected to the action of sanitary and disinfecting applications of any kind without injury. No limitation however, is intended to be made as to the exact material or materials employed in the manufacture of the device.

What is claimed, is:—

1. A device of the character described, comprising a cylindrical comb having an annular series of teeth, a cylindrical sleeve connected with the teeth and disposed within the comb and in spaced relation to the outer wall thereof, said teeth having bores extending therethrough and communicating with the space between said sleeve and wall, a conical closure for the sleeve, and a hood in which the comb is mounted, said hood having an axial opening for the connection of a liquid supply conduit.

2. In a device of the class described, a cylindrical comb having a circumferential series of teeth that are inset with respect to the cylindrical body, a cylindrical sleeve connected with the teeth within the body, said teeth having bores extending therethrough and communicating with the interspace between the sleeve and the cylindrical body, a conical closure for the sleeve, a hood or bonnet in which the cylindrical comb is mounted, said bonnet having an axial opening, and a nozzle connected with said opening and having a flaring bore.

In testimony whereof we affix our signatures.

CHARLES H. SNIDER.
L. D. MAGRATH.
